UNITED STATES PATENT OFFICE.

MARTIN CRONIN, OF WASHINGTON, DISTRICT OF COLUMBIA.

FIRE-EXTINGUISHING ENGINE.

SPECIFICATION forming part of Letters Patent No. 269,777, dated December 26, 1882.

Application filed November 7, 1882. (No model.)

To all whom it may concern:

Be it known that I, MARTIN CRONIN, a citizen of the United States, residing at Washington city, in the District of Columbia, have invented certain new and useful Improvements in a Fire-Extinguishing Engine; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to an improved combined steam and chemical apparatus for extinguishing fires.

The object of my invention is to rapidly extinguish fires by means of a chemical substance 20 injected under mechanical pressure onto the fire, whether combined or not with the ordinary stream of water thrown by a steam fire-engine.

My invention consists in a fire-extinguishing- 25 engine apparatus for ejecting chemical substances, under a mechanical pressure generated by the action of one or more detachable supplemental pumps arranged on the engine, onto the fire. Said chemical substances are in their 30 nature of such a character as to vaporize or be converted into a gas the moment they strike the fire, the gases generated being of such a nature as to antagonize the fire and quickly subdue the flames.

35 My invention further consists in certain other details of construction, which will be more fully described, and pointed out in the claims, reference being had to the accompanying drawings, which form a part of this specification, and in which—

Figure 1 is a side elevation, partly in section, of a steam fire-engine with a storage-tank and pump for ejecting chemical substances onto the fire. Fig. 2 is a top or plan view of the devices shown in Fig. 1. Fig. 3 is a top view of the supplementary pump and tank, partly in section. Fig. 4 is a sectional view of the supplementary pump and the tank on line $x x$. Fig. 5 is an enlarged side view of 50 the pumps and operating mechanism. Fig. 6

is a vertical section of a portable chemical-liquid tank with pump attached. Fig. 7 is a top view of the main-pump pipe, with connections to the supplementary pump. Fig. 8 is a view of a twin connection or combined hose-pipe 55 coupling.

In the drawings, A designates a fire-engine, of any desirable or suitable construction. It is provided with a storage-tank, B, of any desired form, for holding the chemical substances 60 of any kind that will be efficient in subduing flames. The engine is provided with the usual main pump, A', and feed-pump A'', and a supplemental or auxiliary pump, C, which may be operated by the working parts of the engine 65, or detached therefrom. I have shown the pump-rod a of this pump connected to the yoke F by means of a pin, a' , and lug a'' on the said yoke, so that it can be easily detached when not required. Any other suitable operating mechanism may be employed to operate the pump C. It is connected by the pipe b with the storage-tank B, and draws its supply 70 therefrom. An air-chamber, D, is connected by means of pipe c with the supplemental or 75 chemical pump C, by which the pressure is made more steady. The pump C is provided with a nozzle, d, and arranged so that the chemical substances can be thrown onto the fire in a pure state—as, for instance, where 80 the fire has just started, or has made but little headway, or is within easy reach of the firemen; or it can be forced under pressure through pipes e, connecting with the outlet-nozzles f g, into the stream of water which is 85 being thrown onto the fire, and thus the main stream of water is made the vehicle for conveying the chemical substances onto the fire. This is an important feature in the extinguishment of fires, as it frequently occurs that fires 90 originate in the upper stories of high buildings and in locations not easily approached; and, furthermore, it frequently happens that fires have made such headway before an alarm is sounded or before the fire-department re- 95 sponds to the alarm that the men cannot approach near enough to use the chemical appliance alone, and in such cases the chemical substances can be combined with the main stream of one or more engines, and thus are 100

conveyed or forced to a great distance, and the fire can be easily extinguished.

In cases where the necessary supply of the chemical compound or substance cannot be carried on the fire-engine, special tank wagons or tenders G, Fig. 6, can be employed to accompany such engine to the fire, and as fast as the compound is drawn from the engine-tank a fresh supply can be drawn or forced 10 from the tenders into the tank B by means of pumps *h* or other appliances, which are connected by means of a hose to a nozzle, *i*, and a suitable connection, *k*, on the storage-tank B.

In the densely-populated and business portions of cities I may find it desirable and convenient to have stationary tanks or reservoirs 15 for storing the chemical substances, and have connected therewith appliances for forcing said chemicals into the reservoir on the engine; or 20 by means of a "twin coupling," H, such as described in my patent of June 3, 1873, No. 139,550, I may force it direct from the stationary tanks into the water-pump of the engine, or into the stream of water by nozzle *l* after it 25 leaves the pump. Suitable valves are arranged in all the connections or nozzles, as may be required.

E designates the reel for the hose, to be attached to the pump C in case the chemical 30 substances are to be used alone, and by means of suitable valves or cocks a stream of the chemical substance alone or chemicals combined with water can be thrown upon the fire.

With my appliances an ordinary fire-engine 35 may be used in the place of the chemical fire-extinguishers now in use, in which gas-pressure is employed, and by the aid of the pump or mechanical pressure and hose an effective jet can be thrown, as any desired pressure can 40 be obtained at will and a constant stream thrown until the fire is extinguished.

The chemical substance or compound which I propose or prefer to use is what is known as the "Zaffle Fire-Extinguishing Compound;" 45 but I do not confine myself to it, as any chemi-

cal substances or compounds, or combinations of the same which hold absolute sway over combustion may be used. I combine the said compounds with water derived from a fire-plug, reservoir, or other source of supply. A 50 separate steam-engine may, if desired, be used to operate the auxiliary pump.

I am aware that it is not broadly new to combine a fire-extinguishing fluid with a stream of water; also, that such fluids have been carried in tanks with compartments, from which it is ejected on the fire. 55

Having thus described my invention, what I claim, and desire to secure by Letters Patent, is—

1. The combination, in a fire-extinguishing engine provided with a tank for a chemical extinguishing-fluid, of a main water-pump with an auxiliary chemical-pump located on said engine, and constructed to be operated thereby and detached therefrom, substantially as 60 and for the purpose set forth.

2. The combination, in a fire-extinguishing engine provided with a tank for a chemical extinguishing-fluid, of a main water-pump, an auxiliary chemical-pump located on said engine and constructed to be operated thereby, with connections to said tank, the main water-outlet nozzles, an air-vessel, and a separate nozzle for attachment of hose, substantially as 70 75 specified.

3. The combination, in a fire-extinguishing engine provided with a tank for a chemical extinguishing compound, of a main water-pump, an auxiliary chemical-pump located on said engine and operated thereby, and suitable connections, with an auxiliary portable tank for replenishing the tank on the engine, substantially as and for the purpose set forth. 80

In testimony whereof I affix my signature in 85 presence of two witnesses.

MARTIN CRONIN.
